UNITED STATES PATENT OFFICE

2,367,416

SHEET-FEEDING METHOD AND MACHINE

Louis Landaff Matthews, Westerly, R. I., assignor
to Maxson Automatic Machinery Company,
Westerly, R. I., a corporation of Rhode Island

Application August 4, 1940, Serial No. 351,348

19 Claims. (Cl. 271—64)

The present invention relates to methods of and machines for feeding sheet material, and more particularly to the sorting of the sheets during the feeding.

In Letters Patent of the United States 1,942,870, issued January 9, 1934, there is disclosed a sorting machine with the aid of which it is possible to inspect a web as it is unrolled from a roll of paper or the like, prior to the cutting of the web into sheets, and to reject such of the sheets as inspection may show to be defective. The inspection of the traveling web is tiring on the eyes of the operator.

An object of the present invention, therefore, is to provide a new and improved method and machine that shall relieve the operator's eyestrain.

With this end in view, a feature of the invention resides in stopping the travel of the topmost sheet of an underlapped pile of sheets, each for a brief interval, to permit inspection of the said topmost sheet at a time when it is stationary.

Another object of the invention is to provide a novel method and machine for rejecting the topmost sheet of the underlapped pile, if inspection thereof, when stopped, shows it to be below standard.

Other and further objects will be explained hereinafter and will be particularly pointed out in the appended claims.

The invention will now be described in connection with the accompanying drawings, in which Fig. 1 is a diagrammatic view, partly in side elevation and partly in section, and with parts broken away, other parts displaced, and still other parts omitted, for clearness, of a paper-cutting-and-feeding machine embodying the present invention, according to which the topmost sheet of an underlapped pile is stopped for inspection purposes; Fig. 2 is a corresponding plan; Fig. 3 is a view similar to Fig. 1 of a modification; Fig. 4 is a similar view illustrating parts of the machine omitted from Fig. 1, for clearness; Fig. 5 is a similar view of a machine for feeding and sorting previously cut sheets; Fig. 6 is a similar view, showing various parts in relations different from the relations shown in other figures; Fig. 7 is a similar view of a portion of the machine omitted from Fig. 5, because of lack of space on the drawings; Fig. 8 is a fragmentary enlarged view of the lay-boy end of the machine; Fig. 9 is a corresponding plan; Fig. 10 is a fragmentary plan corresponding to Fig. 2, but upon a larger scale; and Figs.

11 and 12 are views corresponding, respectively, to Figs. 18 and 19 of the said Letters Patent 1,942,870.

Figs. 1 to 4 illustrate a paper-sheet-cutting-and-feeding machine of well-known type, such as is commonly employed in paper mills. A web 3 is led from a roll 2 of paper to feed rolls 10, by which the paper is advanced to a rotary cutter 16, mounted upon a shaft 17, and a cooperating stationary bed-knife cutter 15, by which the web is cut into sheets 56 of the desired length. The length of the sheets is determined by the relative adjustment of the speed of the feed rolls 10 and the speed of the cutter 16. As illustrated in Figs. 5 and 7, however, the invention is applicable also to use with sheets previously cut and collected in a stack 12.

After the sheets 56 are thus severed, they are led, at a downward incline, by gravity, toward upper and lower feed rolls 34 and 137 that extend transversely of the machine, respectively above and below, and in engagement with, a series of belts or tapes 6. The roll 34 is shown positioned slightly to the left of the roll 137 to provide a space in which the rolls 34 and 137 and the tapes 6 may bite the heads 62 of the oncoming sheets. The belts or tapes 6 are disposed approximately horizontal, substantially parallel to the bed knife 15, at a level below the level at which the web is fed between the rolls 10. The head 62 of each sheet 56 passes under the roll 34 and over the roll 137 and between these rolls and the tapes 6 by which it is fed further forward toward a lay-boy 4. The tapes 6, driven at relatively high speed, feed the sheets 56, as they come from the cutter, at a speed approximately ten percent greater than the speed of the web 3, as determined by the feed rolls 10. The belts or tapes 6 are mounted around rolls 1, 7 and 8. The head 62 of each sheet becomes gripped by the rolls 34 and 137 and the tapes 6 to pull the sheet taut and away from the next-following sheet, in order to separate the sheets from the cutter and from one another.

Rolls 101 and 102, respectively above and below the upper reaches of the tapes 6, then grip the heads of the sheets to feed the sheets away from the tapes 6, at still greater increased speed, under the tapes 19, and over a bridge 103. The tapes 19 are mounted over rolls 9, 21 and 22, so that their lower reaches extend at a slight downward incline, toward the roll 21.

The roll 102 is shown extending transversely, throughout the width of the machine. The rolls 101, however, are shown as constituted of two

relatively thin slightly separated wheels, positioned near the center of the sheet, one on each side of the said center. So positioned, the rolls 101 cooperate with the roll 102 to grip the head 62 of each sheet near its center, on both sides thereof, which results in feeding the sheet forward square in its own true path, without tilting or swerving. At the moment that the rolls 101 and 102 grip the head 62 of the sheet 56, therefore, they carry the sheet between the tapes 19 and the bridge 103, at high speed, straight forward, but at the said slight downward incline, toward lower tapes 20, shown mounted over rolls 13 and 14. The portions of the tapes 19 between the rolls 21 and 22 then cooperate with the lower tapes 20 to feed the sheets further singly into the lay-boy 4, in which the sheets become stacked. A stop 25 acts upon the forward ends or heads of the sheets to limit their further forward movement. The sheets may be jogged in the lay-boy 4 in the usual manner, so that the sheets become stacked or piled in the lay-boy evenly. A preferred jogging mechanism, illustrated in Figs. 8 and 9, is described more fully hereinafter.

The rolls 101 and 102 and the tapes 19 and 20 are driven by well-known mechanism (not shown) at relatively high speed, say, twice the speed of the feed rolls 10 that drive the web 3. The speed of the sheets, as they enter the lay-boy 4, therefore, may be so high as to tend to buckle the sheets in the lay-boy in a manner that might prevent proper stacking. The portions of the tapes 19 between the rolls 21 and 22 on one side of the sheets 56 and the tapes 20 on the other side restrain the sheets from buckling while traveling at this high speed, but in the lay-boy, there is no such restraining influence.

In order to prevent the sheets from buckling and flying about in the lay-boy 4, the tail of each sheet, after its head has entered the lay-boy, as described in Letters Patent 1,752,648, issued April 1, 1930, is engaged by a cam 67 to slow down the speed of travel of the sheet. As shown more clearly in Fig. 2, the cam 67 may be constituted of two relatively thin slightly separated cams positioned, like the wheels 101, near the center of the sheet, one on each side of the said center. The cams 67 are mounted upon the shaft 69 of the roll 22 so as to engage a roll 71 extending transversely of the machine, like the roll 102, once corresponding to each revolution of the shaft 69. The shaft 69 is driven in timed relation to the cutter 16 by means of a sprocket chain 51 mounted over a sprocket wheel 81 on the shaft 69 and also over a sprocket wheel 74 on a shaft 63. The shaft 63 is driven from the knife shaft 17 by mechanism hereinafter to be described. The drive of the shaft 69 from the knife shaft 17 does not interfere with the separate drive of the tapes 19; such interference is prevented by mounting the rolls 22 loosely on the shaft 69.

As described in the said Letters Patent 1,752,648, issued April 1, 1930, the cam 67 is thus so timed as to rotate, in the direction of the arrow, to cause the tail 23 of each sheet to become engaged between the cam 67 and the roll 71 before the sheet has completely entered the lay-boy 4, thereby to slow down the sheet and prevent it buckling and flying about in the lay-boy. The high speed at which each sheet is fed forward into the lay-boy by the tapes 19 and 20 becomes thereby reduced, as the tail of the sheet 75

enters the lay-boy, thus permitting each sheet to become properly deposited in the lay-boy before the head of the next-following sheet enters the lay-boy. The roll 71 may be an idler or, preferably, it may be positively driven, to aid in feeding the sheets 56 into the lay-boy 4. In this manner, the sheets may be advanced to, and stacked evenly in, the lay-boy, without curling or other defects incident to high speed, though the sheets are, in reality, advanced singly into the lay-boy by the tapes 19 and 20 at quite a high speed.

Before the sheet 56 is permitted to enter the lay-boy, however, it must pass satisfactory inspection by an operator, positioned nearby, as shown in dotted lines in Fig. 1. In order to reduce the strain on the operator's eyes, and to make it easier for him to detect flaws in the sheet, the sheet is brought to a full stop for a brief interval of time.

To stop the travel of the sheet 56, its head 62 is caused to engage a series of stop fingers 161 that normally, as illustrated in Figs. 1 to 5, project above the tapes 6, in the spaces between adjacently disposed tapes. Upon the head 62 of each sheet engaging the stops 161, the sheet is brought to rest upon the tapes 6, permitting inspection of each sheet by the operator at a time when such sheet is stationary. The stop fingers 161 are positioned to the left of the rolls 101 and 102, so that the sheets 56 are stopped on the tapes 6 before they have yet been permitted to reach the rolls 101 and 102.

The stops 161 become automatically lowered periodically, at intervals, from the position illustrated in Figs. 1 to 5, to the position illustrated in Fig. 6, below the tapes 6. This automatic lowering of the stops 161 is effected in timed relation to the operation of the other elements of the machine by means of a rotary cam 159 that is directly driven from the cutter shaft 17 by a sprocket chain 158 mounted over a sprocket wheel 113 upon the shaft 17 and a sprocket wheel 160 that is fixed to the shaft 163 of the cam 159. The cam 159 is thus caused to rotate through a complete revolution once corresponding to each revolution of the cutter shaft 17. The stops 161 will thus become actuated from the effective position of Figs. 1 to 5, to the ineffective position of Fig. 6, and back to the effective position, once during each revolution of the cutter shaft 17, thus to stop once, for inspection purposes, each sheet 56, during its travel toward the lay-boy 4.

The periphery of the cam 159 is circular, except for a slight dwell or cam notch 165. The stops 161 each constitutes one of the arms of a bell-crank lever the other arm 261 of which is provided with a roll 263 that is normally held in engagement with the circular portion of the periphery of the cam 159. Once during each revolution of the cam 159, the roll 263 becomes forced into the cam notch 165 by a spring 157, as illustrated in Fig. 6. It is during this brief interval, when the roll 263 occupies the notch 165, that the stops 161 assume their ineffective position, illustrated in Fig. 6. The next moment, the portion 27 of the cam 159, as the cam continues its rotation in the direction of the arrow, forces the roll 263 out of the cam notch 165, in opposition to the action of the spring 157, on to the circular periphery of the cam 159, forcing the stops 161 into their effective position, illustrated in Figs. 1 to 5.

The operation of the knife 18, the stops 161

and the cam 67 and also, therefore, of the feeding means, is thus synchronized to effect actuation of the stops 161 periodically into and out of the path of feed of the sheet after leaving the cutter 16, and to effect engagement of the tail of the sheet just before it enters the lay-boy 4.

During the brief interval of time during which the stops 161 occupy their ineffective position, illustrated in Fig. 6, below the tapes 6, the tapes 6 become enabled to continue their feeding of the sheet 56 beyond the stops 161, and toward the rolls 101 and 102, the tapes 19 and 20, and the lay-boy 4. During the remainder of the cycle of the operation of the knife 17 and the cam 159, the sheet remains stationary on the tapes 6. As the notch 165 occupies but a very small portion of the periphery of the cam 165, each sheet remains stationary on the tapes 6, for the operator to inspect, during substantially the complete duration of a knife revolution. Defects in the sheet become thus more easily detected and eyestrain is greatly relieved.

It is only when inspection of the stationary sheet 56 shows it not to be defective that the operator permits it to be fed forward toward the tapes 19 and 20 and the lay-boy 4. If the inspected sheet 56 turns out to be defective, the operator will deflect it out of its path of travel toward the lay-boy 4. This he does by pulling upon a rod 29, toward the left, causing it to slide in bearings 31, and resulting in a corresponding pull upon a chain 33. A catch 35 is thus actuated toward the left, about a pivot 37, from its normal effective position, illustrated in Fig. 6, to its ineffective position, illustrated in Figs. 1 to 5. In its ineffective position, the catch 35 releases a cooperating lug 41 that is mounted rigidly, so as to move, with a switch 43. This switch 43 may be constituted, as illustrated in Fig. 2, of a number of spaced switch fingers, aligned transversely of the machine and to the line of feed. The switch fingers and the lug 41 are shown fixedly mounted upon, or integral with, a rod 45, so as to be capable of pivoting with the rod in bearings 40. The release of the lug 41 by the catch 35 permits a spring 47, secured to the tail thereof, on the other side of the pivotal rod 45, to actuate the switch 43, about the pivotal rod 45, from its normal ineffective position, illustrated in Fig. 6, to the effective position of Figs. 1 to 5.

In their normal, ineffective position, illustrated in Fig. 6, the switch fingers 43 are disposed below the lower reach of the tapes 19. The rolls 101 and 102 may then carry the sheets 56, after traveling beyond the stops 161, over the bridge 103, under the tapes 19, and to the tapes 20 and the lay-boy 4, as before described.

The bridge 103 may be constituted of a number of bridge fingers, one integral with each switch finger 43. When in their effective position, however, the switch fingers 43 become positioned in the spaces between adjacent tapes 19, as illustrated in Figs. 1 to 5, stripping the sheet from these tapes 19, and deflecting it on to a guide 49. The guide 49 may be constituted of guide fingers, one integral with each switch finger 43 and bridge 103. These guide fingers will guide the sheet, so as to deliver it to an auxiliary defective-sheet lay-boy 11, shown in Fig. 1.

After the operator lets go his hold upon the rod 29, the switch 43 will become automatically restored to its normal position by mechanism described more at length in the said Letters Patent 1,942,870. This mechanism is illustrated as comprising an arm extension 53 fixedly mounted upon

the pivotal rod 45, and provided with a roll 55 that normally, when the catch 35 is effective, occupies the normal position, illustrated in Fig. 6. In this normal position, corresponding to the position shown in Fig. 14 of the said Letters Patent 1,942,870, the roll 55 rests upon the high point of a cam roll 59.

Upon the release of the catch 35, the action of the spring 47, in pivoting the lug 41 upward, from the position of Fig. 6 to that of Figs. 1 to 5, causes the extension 53 to become pivoted downward, thus forcing the roll 55 also downward. The roll 55 will then be permitted to enter a cam-opening part 57 of an interior cam groove 61 that extends around the center of the cam roll 59. The cam-opening part 57 is provided upon the periphery of the cam roll 59, commencing at a point adjacent to the high point of the cam roll 59, and from there on communicating with the remaining portion of the interior cam 61. Once the roll 55 has entered the opening 57, therefore, it is confined by the interior cam 61 until after a complete revolution of the cam roll 59. The roll 55 is illustrated in Figs. 1 to 5 as still confined by the interior cam 61. Owing to the shape of the interior cam 61, the roll 55 will be positively forced to ride out of the cam 61, and onto the periphery of the cam roll 59, at the end of a complete revolution of the cam roll 59, a spring-pressed latch 91 yielding about its pivotal point 93 to permit this. The lug 41 is thus caused to return to its normal position, illustrated in Fig. 6.

If the operator has meanwhile let go of the rod 29, a spring 39 has restored the catch 35 to its normal position, illustrated in Fig. 6. The catch 35 becomes thus enabled to reengage the lug 41, preventing the roll 55 from again entering the cam opening 57 until after the rod 29 is again actuated.

The parts are so timed that the switch 43 shall open just before the defective sheet is released by the stops 161 and shall close again before the next sheet has reached these stops. The operator will manipulate the rod 29 once for each defective sheet that he sees deposited on the tapes 6. This he may do substantially at any time, for nothing normally interferes with his pulling upon the rod 29, to the left, to release the catch 35. If several sheets in succession are seen to be defective, the operator will maintain his hold upon the sliding rod 29, to cause the catch 35 to occupy continuously its ineffective position, and the switch 43 to be maintained continuously in its effective position, illustrated in Figs. 1 to 5, until all the successively following defective sheets have thus become side-tracked into the auxiliary lay-boy 11. Though the operator may manipulate the rod 29 at any time, however, the switch 43 can not be actuated into the path of travel of the defective sheet until after the lapse of a time interval, determined by the construction of the cam 59 and its gearing to the cutter 17, as presently to be described. The roll 55 can not enter the cam-opening part 57 until the cam 59 has been rotated to a suitable position, as is described in the said Letters Patent 1,942,870, and as is clear from the drawings.

The cam roll 59 is operated in timed relation with the other elements of the machine, as described, by driving it from the shaft 163 of the cam 159 which, as before explained, is driven directly from the cutter shaft 17. To this end, the shaft 163 of the cam 159 is provided with a further sprocket wheel 60. A sprocket chain 58,

mounted over the sprocket wheel 80 and a sprocket wheel 42 upon the shaft 63, drives the cam roll 59 so as to effect one complete revolution of the cam 59 corresponding to each revolution of the cutter shaft 17 and the cam shaft 63.

As before explained, the embodiment illustrated in Fig. 5 is adapted to the feeding and sorting of previously cut sheets 56. These may be fed, in lapped relation, from beneath the stack 12, in any well-known manner, as, for example, by the mechanism illustrated and described in Letters Patent 690,167 granted December 31, 1901 to Charles B. Maxson. In the beginning, the speed of travel of the sheets on the table 5 is comparatively low. The head 62 of the most advanced sheet reaches, in time, the bite between the tapes 6 and tapes 79 above the tapes 6. The tapes 79 are mounted over rolls 80 and 66, with the roll 80 above the roll 1, so that the head 62 of the sheet is gripped therebetween. As soon as the head 62 of each sheet reaches the bite between these rolls 1 and 80, these rolls increase the speed of travel of the sheets. At this increased speed, the sheets are fed by the tapes at so high a speed as to separate each sheet from under the stack 12 and advance it toward the rolls 34 and 137 singly. Each sheet 56 reaches the stops 161, therefore, in the same condition as before described in connection with the feeding of the sheets from the cutter 16, permitting ready inspection thereof. The operation of the machine illustrated in Figs. 5 and 7 subsequent to the inspection may be the same as before described.

During the period of time when any particular sheet 56 is held stationary by the stop fingers 161, the next-following sheets successively cut by the cutter 16, of course, are still being fed forward along the same path toward the stops 161, at the same relatively high speed of the tapes 6, past the point at which the roll 137 is positioned. Such next-following sheets must necessarily, therefore, lap the stationary sheet engaged by the stops 161. An overlapping delivery, however, would interfere with the inspection of the stationary sheet by the operator.

According to a feature of the present invention, therefore, provision is made for underlapping the next-following sheet or sheets under the stationary sheet. To this end, the tail 23 of the sheet 56, the head of which has been engaged by the stops 161 to stop the further travel of the sheet, is maintained slightly raised above the tapes 6. This permits interposing the head 62 of the next-following sheet under the said raised tail 23 of the stationary sheet, and between the said raised tail 23 and the tapes 6. By the time the head of the next-following sheet becomes stopped by the stops 161, its tail 23 too will similarly become raised to permit the head of the directly next-following sheet to travel thereunder, in similar fashion. At each periodic interposition of the stops 161 in the path of travel of the sheets, therefore, not only is the head 62 of the sheet engaged by the stops, but the tail 23 thereof becomes raised by the rings 86. An underlapping delivery is thus provided that does not interfere with the inspection of the uppermost stationary sheet of the underlapping pile, when held stationary by the stops 161 on the tapes 6.

The preferred mechanism for raising the tail 23 of the stationary sheet, to permit of this underlapping delivery, comprises a plurality of rings 75

86 that may be constituted of a phenol-composition or other suitable product, like Bakelite, mounted upon the roll 137 which may be constituted of steel tubing. As disclosed more fully

in Letters Patent 2,261,973, issued November 11, 1941, the Bakelite rings 86 may extend all the way across the machine, close enough to one another so that there shall be just sufficient room between each two successively disposed rings 86 for the passage of a tape 6 between them. A plurality of rings of smaller diameter than the rings 86 are thus exposed on the roll 137 alternating with the rings 86 and each engaging one of the tapes 6.

15 The upper portions of the Bakelite rings 86, being raised above the level of the tape 6, successively raise the successive portions of each sheet 56, as it is fed thereover, slightly above the tapes 6. This raising is effected continuously,

20 beginning with the head 62 of each sheet 56 and ending with the tail 23 thereof. The head 62 of each sheet will become raised in this manner at a time when the tail 23 of the next-preceding sheet is still raised, and before the said next-

25 preceding sheet has been moved away toward the lay-boy 4. By positioning the roll 137 at a distance from the stops 161 slightly less than, or even substantially equal to, the length of the sheets being fed, the tail 23 of each stationary

30 sheet on the tapes 6 will become raised at the moment that its head 62 becomes engaged by the stops 161, and will be maintained so raised until the stops 161 release the sheet. It is possible to adjust the position of the rolls 34 and 137 as a unit, to provide for different-length sheets, by any suitable mechanism, such as that described in Letters Patent 1,545,910, issued July 14, 1925, to Charles B. Maxson, or in the said Letters Patent 2,261,973.

40 Ordinarily, the above-described underlapping delivery may usually be brought about without any static-electricity difficulties caused by friction between the stationary sheet on the tapes 6 and the next-following sheet or sheets fed thereunder. This is because a film or layer of air usually forms between these sheets, resulting from the manner in which one sheet is fed under another. The formation of this air layer may, how-

45 ever, be further facilitated with the aid of a very light blast of air at a point above the rings 86 of the roll 137 and below the tail 23 of the stationary sheet raised thereby. This air blast may be provided in any desired manner, as from 50 a nozzle or nozzles 68, positioned over the roll 137, and perhaps slightly to the left thereof, so as to direct the blast between the tail 23 of one sheet and the head 62 of the next-following sheet.

Ordinarily, there will be but one sheet on the 55 tapes 6 underneath the stationary sheet stopped by the stops 161. Irrespective of the number of sheets 56, whether two or more than two, in the underlapped pile on the tapes 6, the feed of the topmost sheet of this pile will remain stopped

60 during nearly a complete revolution of the knife 16 and the cam 159, as before explained, until the stops 161 become lowered to their ineffective position, during the very brief period when the roll 263 enters the cam notch 165. The operator

65 will be enabled to inspect the stationary sheet 56, therefore, throughout the period of time when the cutter 17 and the cam 159 perform this nearly complete revolution.

In order that the topmost sheet 56 of the un- 70 derlapped pile may remain stationary for in-

spection purposes during so long a period, it is necessary that the sheet 58 previously disposed thereover be fed away from the cutters 15, 16 at a speed greater than the speed of travel of the web 3 to the cutters. If the sheets were fed singly, the increase in speed that would be required for this purpose would be considerable; perhaps as much as one hundred per cent. In the absence of such great increase in speed, it would not be possible to hold the said topmost sheet 58 of the pile stopped on the tapes 6 for a period nearly so great as the time between successive knife cuts.

A sheet that would be fed forward at such relatively high speed toward the stops 161 could not safely be permitted to engage these stops head-on, as such head-on engagement would result in damaging the heads of the sheets, besides causing the sheets to re-bound and fly about, thus interfering with further smooth operation.

By underlapping the sheets, however, it is not necessary to feed the sheets away from the cutters at such high speed; a ten per cent increase, for example, as before stated, is quite sufficient. The sheets may, therefore, be fed into engagement with the stops 161 without any harmful effects whatever.

Sheets of even very light stock are accordingly very readily handled according to the present invention. The sheets are not damaged by engagement with the stops 161 because their heads engage these stops with very light contact. And the sheets can not buckle and fly about, because they are restrained from doing so by the tapes 6 beneath and the next-following sheets above them.

There is still another advantage attendant upon the underlapping delivery. Through feeding the sheets at such relatively high speed away from the cutters, the tail 23 of each sheet becomes considerably separated from the head 62 of the next-following sheet. If the sheets were fed singly, instead of being underlapped, they would arrive at the place where they are to be inspected, "shooting," at high speed. Disregarding the fact that they would arrive with corners flying up and down and side-wise, the operator would see a fast-moving object suddenly come to rest in front of her. She would undertake to scan it; but while she was attempting to do so, the sheet would suddenly start away quickly. Though her eyes had been focussed on the sheet that she was looking at, at a certain level, at the very next instant her focus would become destroyed by the disappearance of the sheet. All that she would now be looking at, in front of her, would be a blank section of space, except for the presence of the tapes 6. The next moment, another sheet would cover those tapes, producing a change both of color and of content.

Experiences of this kind are very trying on the eyes, requiring that the operator take frequent rest intervals, during which the machine is idle.

The underlapping delivery of the present invention has fully solved all these difficulties. The operator is not required to look intermittently at a blank space into which sheets come flying at rapid, separated intervals of time. There are no sudden changes of vision presented to her eyes by rapidly arriving and departing sheets, and there is no sudden change of focal distance for the eyes. The operator is always looking at the top sheet of the underlapping pile, at the same place, under the same conditions of focus, and

the color of this top sheet is continuously the same.

Experience shows that not only do the operators feel no ill effects, but they become less tired than when sorting the sheets by hand from a stationary pile on a sorting table.

Whether the sheets be fed previously cut from the pile 12, as illustrated in Figs. 5 and 7, or whether they be cut in the machine from the web 3, the top sheet of the underlapped pile will be led off by the rolls 101 and 102, as before stated, toward the lay-boy 4, at greater speed, as soon as it becomes released by the stops 161, thereby exposing to inspection the next-adjacent sheet of the pile directly under the said top sheet. If this topmost sheet is standard, it will be permitted, at the will of the operator, to continue its travel toward the right, and into the lay-boy 4; if this sheet is defective, however, it will be deflected by the operator in another direction, toward the lay-boy 11.

The lay-boy 4 is automatically lowered, from time to time, to maintain approximately uniform the level of the sheets that are stacked therein. As they are delivered into the lay-boy 4, the sheets are automatically counted, and thin indicating paper tags 24 are automatically inserted between adjacent predetermined sheets 104 and 106 at the top of the pile or stack in the lay-boy, at the completion of each count, to separate or mark the bundles or reams of sheets so delivered and counted.

The counting and tag-inserting mechanism may be the same as is illustrated and described in the said Letters Patent 1,942,870, and also in Letters Patent 1,611,476, granted December 21, 1926, and 1,613,182, granted January 4, 1927, to the said Charles B. Maxson, to which reference may be made for details not fully disclosed herein. The tagging mechanism, as there described, comprises feed rolls 26 and 27 (Fig. 1) intermittently driven from a shaft 44 (Figs. 2, 4 and 10) through a train of gearing 28. The feed rolls 26 and 27 and the gearing 28 are shown in Fig. 1 only for purposes of clarity, and in order not to confuse the drawings by too much detail in any particular figure. The figures are not drawn to scale, and many parts are omitted therefrom and other parts distorted, also in the interest of clarity.

These feed rolls 26 and 27 automatically advance a paper strip 34 intermittently as it is unwound from a roll 36. The end 38 of the paper strip is thus, at the proper time, intermittently inserted by the feed rolls 26 and 27 between the said two adjacent sheets 104 and 106 of the stack of sheets in the lay-boy 4 and, after it is severed by knives, constitutes a tag 24. The knives occupy positions indicated at 30 and 32, as more clearly illustrated in the said Letters Patent 1,613,182. The shaft 44 is continuously rotated, as described in the said Letters Patent, but does not become effective to actuate the feeding rolls 26 and 27 until at the end of each cycle of operation of the counter, after a full ream or other desired number of sheets has been delivered into the lay-boy 4.

This result is attained, as explained more fully in the said Letters Patent 1,942,870, and as illustrated in Figs. 10 to 12 herein, through the medium of a pawl 46 that is pivotally mounted at 52 upon a collar 54 that is pinned to the shaft 63 (as is clearly visible in Fig. 13 of the said Letters Patent 1,942,870). The pawl 46, therefore, rotates continuously with the shaft 63,

and as the rotation of the latter is timed with the revolutions of the knife 16, the pawl 46 makes one revolution corresponding to each revolution of the knife 16. The number of revolutions of the pawl 46, therefore, is a measure of the number of sheets cut by the knife 16, and that would, under normal conditions, be delivered into the lay-boy 4. The pawl 46 normally engages a lug 48 that is provided upon the hub or collar 50 of a sprocket wheel 65 that is loosely mounted upon the shaft 63 so as to rotate thereabout. In thus rotating in a circular path with the shaft 63, therefore, the pawl 46 normally carries the collar 50 and the sprocket wheel 65 with it about the axis of the shaft 63.

Though the sprocket 65 itself is loose, it is driven forward to turn the shaft 44 by means of a ratchet-and-pawl mechanism, as illustrated in Figs. 9 to 13, 18 and 19 of the said Letters Patent 1,942,870 and Figs. 10 to 12 herein.

A sprocket chain 64 (Figs. 2, 4 and 10) is mounted over the sprocket wheel 65 and also over a sprocket wheel 67 upon the shaft 44. As the rotation of the shaft 44 is, therefore, timed to the rotation of the rotary knife 16, because driven from the knife-driven shaft 63, it is a measure of the number of sheets that are cut by the knife 16 and that would normally be stacked in the lay-boy. By connecting the shaft 44 to a counting disk 97, then, it is possible to count the number of sheets cut by the knife 16. The details of the counter may be found described in the said Letters Patent 1,611,476. The hand-wheel mechanism shown more particularly in Fig. 13 of Letters Patent 1,862,797, issued June 14, 1932, to Matthews, may also be employed to provide simultaneous adjustment for the cutter shaft 17, the switch shaft 63, and the counter shaft 44.

Owing to the side-tracking of the defective sheets into the lay-boy 11, the number of sheets separated by the tags 24 will be reduced accordingly, and it becomes necessary to correct the count for the number of defective sheets removed by the switch 43. The mechanism for effecting this result is illustrated in Figs. 10 to 12 hereof, as well as in the said Letters Patent 1,942,870. As therein explained, the said mechanism above-described for maintaining open the switch 43 through the medium of the interior cam 61 is employed also to correct the count of the counter, through the medium of the before-mentioned sprocket wheel 65, loosely mounted on the shaft 63. When the roll 55 enters the cam opening 57, as before explained, the pivoting rod 45 is tilted therewith. An arm 369 that is fixed to the pivoting rod 45 is, therefore, tilted also, and its end 371 is thus brought against a wall 13 of a collar or disc 72. The collar or disc 72 is loosely mounted upon a reduced hub 85 of the collar 54, so as to be free to rotate about the hub 85. The collar or disc 72 binds frictionally against the hub 85, and is normally, therefore, rotated with the collar 50. When the end 371 of the arm 369 engages the wall 13, however, the collar or disc 72 is prevented from rotating further.

The collar or disc 72 has also a gate 70 that normally is to one side of the lug 48, as shown in Fig. 12. Under normal conditions, therefore, the pawl engages the lug 48, as before described, and the collar 50, with its sprocket wheel 65, and the collar or disc 72 rotate together with the collar 54 as a unit. When the end 371 of the arm 369 engages the wall 13, however, and the collar or disc 72 is stopped rotating, in consequence, the further rotation of the collar 50 by

the pawl 46 will soon carry the lug 48 to a position where the gate 70 overlies or covers the lug 48, as shown in Figs. 6 and 10. Upon reaching the wall 78 of the gate 70, the pawl 46, as shown in Fig. 10, will ride up the wall 78 and out of engagement with the lug 48, whereupon the shaft 44 will cease rotating and the counter will stop counting. The lug 48 will thus be left behind the gate 70, in the position of Fig. 10. So long as 10 the gate 70 continues to overlie the lug 48, the continuously rotating pawl 46 can not engage the lug 48, but rides idly over the gate 70, as illustrated in Figs. 6 and 10 of the said Letters Patent 1,942,870. The sprocket wheel 65 is therefore stopped rotating further, the rotation of the shaft 44 is correspondingly stopped and the counter is not further actuated. The operation of the counter becomes thus interrupted during the switching out of a defective sheet, so that the 15 number of sheets delivered into the lay-boy 4 and the indications of the counter are caused to tally.

When the switch 43 resumes its normal position, the sheets will again be led from the cutter 16 to the tapes 19 and 20 and, by them, to the lay-boy 4. The count should, therefore, again be resumed. This is effected by the arm 369 resuming its normal position, together with the switch 43. This is because both the switch 43 and the arm 369 are fixed to the same pivoting rod 45. The wall 13 becoming thus released from the restraining influence of the end 371 of the arm 369, the frictional binding of the collar 72 against the hub 85 will cause the collar 72 to resume its rotation about the axis of the shaft 63 together with the collar 54. The gate 70 will accordingly be moved away from the positions of Figs. 6 and 10 and into the positions of Figs. 5 and 9 of the said Letters Patent 1,942,870.

Upon the gate 70 becoming displaced from the position of Figs. 6 and 10 into that of Figs. 5 and 9 of the said Letters Patent 1,942,870, the pawl 46, during its next journey around with the shaft 63, will again become pressed into engagement with the lug 48 by a spring 78. The pawl 46, continuing its rotation, will now again carry the sprocket 65 with it, and the latter will, through the sprocket chain 64 and the sprocket wheel 67, again cause rotation of the shaft 44 and actuation of the counter controlled thereby.

The gate 70 is shown provided with a wall 78 similar to the wall 13, and the wall 78 is formed upon a gate 77 similar to the gate 70. The end 371 of the arm 369 may engage either the wall 13 or the wall 78, whichever happens to be nearer at the time that the switch 43 is actuated, and the other gate 70 or 77, as the case may be, will then be moved behind the lug 48 to disengage the pawl 46 therefrom.

Though the knife 16 operates continuously, therefore, the said loosely mounted sprocket wheel 65 is rotated only when the sheets 56 enter the lay-boy 4, so as to maintain the count accurate.

Cases occur where a sheet is too defective for stacking in the lay-boy 4, and yet too good to be discarded in the lay-boy 11. In such cases, a second switch may be employed, between the switch 43 and the lay-boy 4, to deflect to a further lay-boy (not shown) such of the sheets of intermediate quality. Provision will then be made to correct further for the operation of the counter by employing a second sprocket like the sprocket 65, geared to the first-named sprocket 65 on the shaft 63. Both sprockets 65 will control the cor-

rection of the counter in the same manner, so that each deflection of a sheet from the lay-boy 4, whether into the lay-boy 51 or the said other lay-boy (not shown) by the additional switch will result in like correction of the count.

The preferred jogging mechanism illustrated in Figs. 8 and 9 may be of the type illustrated and described in Letters Patent 2,261,972.

A sprocket 83, driven by a chain 84 from any available power source (not shown), operates a shaft 82 on which are mounted a bevel gear 78 and an eccentric connecting head 87. The eccentric connecting head 87 is connected by a rod 88 to a connecting head 89, fastened to a rock shaft 190. The rock shaft 190 is provided with jogger fingers 107 the upper ends of which oscillate or rock back and forth in the line of feed to engage the rear edges of the sheets deposited upon the top of the stack or pile in the lay-boy 4. One or more, usually several, of these endwise back-and-forth jogging movements of the fingers 107 may take place against the rear edge of each sheet. By means of this jogging, the papers 56 are carefully pushed into the proper position in the lay-boy 4, with their heads in engagement with the front stops 25.

Stationary fingers 111, alternately spaced with respect to the movable fingers 107, as illustrated more particularly in Fig. 14, and mounted rigidly upon a fixed supporting rod 94, determine the position of the rear edge of the pile of papers in the lay-boy 4. The stationary fingers 111 are provided with bearings in which the rock shaft 190 is mounted loosely, to enable it to turn freely therein. As viewed in Fig. 13, the lower portions of the movable fingers 107 are somewhat concealed, in all positions of the latter, by the stationary fingers 111.

The bevel gear 78 meshes with another bevel gear 109 that is pinned to a shaft 96 that runs lengthwise of the machine or parallel to the flow of paper into the lay-boy. The rotation of this shaft 96 reciprocates connecting heads 121 and 98 that are cam-mounted on the shaft 96, their cams 108 and 110 turning freely in the connecting heads 121 and 98 to convert their rotary motion into a reciprocal motion, in bearings 116, of rods 115 and 117 to which the heads 98 and 121 are connected by pivoting studs 112 and 114 to bell cranks 99 and 100. As the cams 108 and 110 in the connecting heads 121 and 98 are fastened to the shaft 96, with their high sections 180 degrees apart relative to each other, the rod 115 will travel to the left when the rod 117 travels to the right, and vice versa. Riding on each of these two rods 115 and 117 is a T-shaped bracket 119. The brackets are secured to the respective rods 115 and 117 in any desired way, as by means of thumb screws 118 and 120, at 90 degrees to the respective rods. The stem of the T runs back and forth, by means of rollers 122 rolling on an angle iron 105. Suspended from and attached to each bracket 119 is a sheet steel side jogger blade 123. As the jogger casting 119 is caused to move with the rods 115 and 117, the blades are caused to travel in and out, or toward and from each other. When moving toward each other, they engage the sides of the paper sheets at the top of the pile in the lay-boy 4 to jog the sheets sideways, as the fingers 107 jog them endwise.

The end joggers 107 thus act upon the rear edges of the upper sheets 56 in the lay-boy, and the side joggers 123 close in upon the opposite sides of the said upper sheets, to prevent their spreading sideways.

The pile or stack of papers in the lay-boy 4 is automatically lowered by degrees to maintain the top of the pile at substantially constant height, so as to enable the stream of overlapped sheets to enter the lay-boy freely, without hindrance by the accumulated sheets already in the pile. This may be effected in any desired way, as by the means disclosed in Letters Patent 1,545,912, issued July 14, 1925, to Charles B. Maxson.

In accordance with the present invention, therefore, a unitary machine is provided for performing, in a single operation, the cutting of paper or other sheets of the exact size desired from a roll, sorting the sheets, stacking and jogging them in the lay-boy 4, counting them, correcting the count to allow for the sheets deflected into the auxiliary lay-boy 11, and tagging the sheets into reams. The sheets are fed to the stops 161 in the form of an underlapped pile, preferably of two sheets. The top sheet of the pile is removed at greater speed, so as to expose the next sheet thereunder. The operator is enabled to inspect the sheet at a time when the sheets is stationary. As the time of inspection may be nearly equal to the relatively large period of revolution of the cutter knife, if a cutter knife is employed, ample time is afforded for full and careful inspection, without eyestrain. The inspection of the successive top sheets may be effected at a time when these sheets are stationary, without any more eyestrain than is involved in successively turning the pages of a big book.

Owing to the construction of the cam 59 and its cooperating parts, and the consequent accurate timing of the switch 43 to deflect the particular sheet that is shown to be defective, the operator is not confronted with the necessity for exercising great care as to the time when he pulls upon the rod 29 to deflect such sheet or sheets as may turn out to be defective. He may pull upon the rod 29 at any time, in the assurance that the switch fingers 43 will not operate any sooner nor any later than is necessary to engage the head of the sheet to be deflected, at the proper time, and the switch will be accurately returned to its ineffective position, in time not to deflect the next-following sheet. If the operator should desire to deflect the next-following sheet also, this may be done by again pulling upon the rod 29, or he may continue to retain his hold upon the rod 29, as before explained.

A description of many portions of the machine an understanding of which is not essential to an understanding of the present invention has purposely been omitted and many parts of the machine have purposely not been illustrated in order not to detract attention from features of essential novelty. Fuller explanations of such portions of the machine will be found in the Letters Patent above referred to. It will be understood that the features of novelty may be embodied in other machines and in machines of other types and that modifications may be made by persons skilled in the art without departing from the spirit and scope of the invention as defined in the appended claims.

What is claimed is:

1. A method of feeding sheets that comprises feeding successive sheets along a predetermined path at relatively high speed past a predetermined point and, during the feeding of each sheet, continuously moving out of the path, at the point, successive portions of the sheet, beginning with the head of the sheet and ending

with the tail of the sheet, reducing the speed of each sheet when the tail thereof reaches the point, and moving the head of each sheet out of the path at the point at a time when the tail of the next-preceding sheet is out of the path at the point.

2. A method of feeding sheets that comprises feeding successive sheets along a predetermined path at relatively high speed past a predetermined point, moving the tails of the sheets out of the path at the point, reducing the speed of each sheet when the tail thereof reaches the point, lapping the head of each sheet under the tail of the next-preceding sheet at the point, and supplying an air blast between the head of each sheet and the tail of the next-preceding sheet.

3. A method of feeding sheets that comprises feeding successive sheets along a predetermined path at relatively high speed past a predetermined point and, during the feeding of each sheet, continuously moving out of the path, at the point, successive portions of the sheet, beginning with the head of the sheet and ending with the tail of the sheet, reducing the speed of each sheet when the tail thereof reaches the point, moving the head of each sheet out of the path at the point at a time when the tail of the next-preceding sheet is out of the path at the point, and supplying an air layer between the head of each sheet and the tail of the next-preceding sheet.

4. A machine of the character described having, in combination, means for feeding sheet material, means for cutting the material into sheets, means for feeding the sheets in the form of an underlapped pile with the head of each sheet disposed forward in the line of feed of the sheets below it in the pile, a stop for stopping the top sheet of the pile, and means for actuating the stop periodically into and out of the path of feed of each top sheet of the pile in synchronism with the operation of the cutting means.

5. A machine of the character described having, in combination, means for feeding sheet material, means for cutting the material into sheets, means for feeding the sheets, a stop in the path of feed of the sheets, means for actuating the stop out of and into the path of feed of the sheets, a switch for deflecting the sheets after they have passed the stop, means for actuating the switch, and means for operating the stop and the switch in synchronism with the cutting means.

6. A machine of the character described having, in combination, means for feeding sheets, means for raising the tail of each sheet, means cooperating with the feeding means for feeding the head of the next-following sheet between the first-named feeding means and the tail of the previously fed sheet, and means for injecting an air blast between the said head and the said tail.

7. A machine of the character described having, in combination, means for feeding sheets, a stop for engaging the head of the sheet to stop the feed of the corresponding sheet, means for raising the tail of the stopped sheet, means cooperating with the feeding means for feeding the head of the next-following sheet under the tail of the stopped sheet, and means for injecting an air blast between the said head and the said tail.

8. A machine of the character described having, in combination, means for feeding successive sheets along a predetermined path at relatively high speed past a predetermined point, means

operable during the feeding of each sheet for continuously moving out of the path, at the point, successive portions of the sheet, beginning with the head of the sheet and ending with the tail of the sheet, and means for reducing the speed of each sheet when the tail thereof reaches the point, the moving means being operable to move the head of each sheet out of the path at the point at a time when the tail of the next preceding sheet is out of the path at the point.

9. A machine of the character described having, in combination, means for feeding successive sheets along a predetermined path at relatively high speed past a predetermined point, means operable during the feeding of each sheet for continuously moving out of the path, at the point, successive portions of the sheet, beginning with the head of the sheet and ending with the tail of the sheet, means for reducing the speed of each sheet when the tail thereof reaches the point, the moving means being operable to move the head of each sheet out of the path at the point at a time when the tail of the next preceding sheet is out of the path at the point.

10. A machine of the character described having, in combination, a tape for feeding sheets, a stop for stopping the sheets, and a roll positioned rearward of the stop in the line of feed at a distance somewhat less than the length of a sheet in order that it may raise the tail of the sheet at a time when it is engaged by the stop to permit the head of the next-following sheet to be fed in over the roll and under the said tail.

11. A machine of the character described having, in combination, means for feeding sheet material, means for cutting the material into sheets, means for feeding the sheets in the form of an underlapped pile, and a stop for stopping the top sheet of the pile.

12. A machine for feeding sheets having, in combination, means for raising the tail of each sheet, means for feeding the head of each sheet under the raised tail of the next-Previously-fed sheet, and means for injecting an air blast between the said head and the raised tail of the said next-Previously-fed sheet during the feeding of the said head under the said raised tail of the said next-Previously-fed sheet.

13. A machine for feeding sheets having, in combination, a stop for engaging the head of each sheet fed to stop the sheet, means for raising the tail of the stopped sheet, means for feeding the head of the next-following sheet under the raised tail of the stopped sheet, and means for injecting an air blast between the said head and the said raised tail during the feeding of the said head under the said raised tail.

14. A method of feeding sheets successively that comprises raising the tail of each sheet, feeding the head of each sheet under the raised tail of the next-Previously-fed sheet, and injecting an air blast between the said head and the said raised tail of the said next-Previously-fed sheet during the feeding of the said head under the said raised tail.

15. A method of feeding sheets successively that comprises engaging the head of each sheet fed to stop the sheet, raising the tail of each stopped sheet, feeding the head of the next-following sheet under the raised tail of the stopped sheet, and injecting an air blast between the said head and the said raised tail during the feeding of the said head under the said raised tail.

16. A method of feeding sheets of predeter-

mined length that comprises feeding successive sheets along a predetermined path past a first point, engaging the heads of the sheets at a second point spaced from the first point in the path a distance substantially equal to or slightly less than the predetermined length to stop the sheets, raising the tail of each stopped sheet, feeding the head of the next-following sheet under the raised tail of the stopped sheet, and injecting an air blast between the said head and the said raised tail during the feeding of the said head under the said raised tail.

17. A machine for feeding sheets of predetermined length having, in combination, means for feeding successive sheets along a predetermined path past a first point, means for engaging the heads of the sheets at a second point spaced from the first point in the path a distance substantially equal to or slightly less than the predetermined length to stop the sheet, means disposed at the first point for raising the tail of the stopped sheet to enable the head of the next-following sheet to be fed under the raised tail, and means for injecting an air blast between the said head and the said raised tail during the feeding of the said head under the said raised tail.

18. A machine for feeding flexible sheets constituted of paper and the like having, in combination, a flexible-sheet conveyor constituted of a plurality of tapes extending from one side to another side, upper and lower feed rolls disposed transversely of and in engagement with the conveyor, the upper feed roll being disposed above the conveyor, the lower feed roll being disposed below the conveyor, and means for advancing sheets at a downward incline from above and to the said one side toward the said other side to the feed rolls and the conveyor, the upper feed roll being disposed slightly to the said one side of the lower feed roll to provide a space between the feed rolls in which the feed rolls and the conveyor may bite the heads of the sheets as they are advanced at the said downward incline

to the feed rolls and the conveyor, whereby the heads of the sheets will pass under the upper feed roll and over the lower feed roll and between the feed rolls and the conveyor to enable the feed rolls and the conveyor to grip the heads of the sheets in order to feed the sheets toward the said other side, the lower feed roll being provided with a plurality of rings of greater diameter than that of the lower feed roll disposed in the spaces between the tapes of the conveyor.

19. A machine for feeding flexible sheets constituted of paper and the like having, in combination, a flexible-sheet conveyor constituted of a plurality of tapes extending from one side to another side, upper and lower feed rolls disposed transversely of and in engagement with the conveyor, the upper feed roll being disposed above the conveyor, the lower feed roll being disposed below the conveyor, means for advancing sheets at a downward incline from above and to the said one side toward the said other side to the feed rolls and the conveyor, the upper feed roll being disposed slightly to the said one side of the lower feed roll to provide a space between the feed rolls in which the feed rolls and the conveyor may bite the heads of the sheets as they are advanced at the said downward incline to the feed rolls and the conveyor, whereby the heads of the sheets will pass under the upper feed roll and over the lower feed roll and between the feed rolls and the conveyor to enable the feed rolls and the conveyor to grip the heads of the sheets in order to feed the sheets toward the said other side, the lower feed roll being provided with a plurality of rings of greater diameter than that of the lower feed roll disposed in the spaces between the tapes of the conveyor, and a stop disposed at the said other side of the conveyor a distance substantially equal to or slightly less than the length of the sheets for engaging the heads of the sheets to stop the sheets with their tails raised above the conveyor in engagement with the rings.

LOUIS L. MATTHEWS.
